UNITED STATES PATENT OFFICE

100,614

DESIGN FOR A SHOE

Charles H. Caldwell, Brockton, Mass., assignor to
George E. Keith Company, Campello, Mass., a
corporation of Massachusetts

Application June 1, 1936, Serial No. 62,934

Term of patent 3½ years

To whom it may concern:

Be it known that I, Charles H. Caldwell, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side view of the same.

The design is substantially the same on both sides of the shoe.

The essential feature of the invention resides in the organization of rectangular elements of design, especially including the contrasting rectangular areas as shown. As the design is applicable to shoes of various shapes and styles the representation of shoe is merely conventional, for showing an application of the design.

I claim:

The ornamental design for a shoe, as shown and described.

CHARLES H. CALDWELL.
